UNITED STATES PATENT OFFICE.

GEORGE C. CHASE, OF EAST ORANGE, NEW JERSEY, ASSIGNOR TO CHASE ADDING MACHINE CORPORATION, OF ORANGE, NEW JERSEY, A CORPORATION OF DELAWARE.

REGISTER.

1,330,682.

Specification of Letters Patent. Patented Feb. 10, 1920.

Application filed November 8, 1917. Serial No. 200,910.

To all whom it may concern:

Be it known that I, GEORGE C. CHASE, a citizen of the United States, resident of East Orange, in the county of Essex and State 5 of New Jersey, have made a certain new and useful Invention in Registers; and I declare the following to be a full, clear, and exact description of the same, such as will enable others skilled in the art to which it appertains to make and use the invention, reference being had to the accompanying drawings, and to letters or figures of reference marked thereon, which form a part of this specification.

15 Figure 1 is a vertical section of a portion of a register embodying the invention.

Fig. 2 is a section on the line 2—2, Fig. 1.

Fig. 3 is a section on the line 3—3, Fig. 1.

20 Fig. 4 is a detail side view of a frame plate.

Figs. 5 and 6 are detail side and edge views of a key.

Figs. 7 and 8 are detail side and plan views of a latch.

25 The invention has relation to the frame structure and key-stem structure of adding machines and registers having a series of depressible denominational keys, an object being to facilitate the assembly of the key stems in the machine. Another object is to 30 provide a machine wherein more room is afforded for the working parts; these working parts are more accessible for examination, lubrication and repair, and the machine is capable of more economical manufacture. Other objects and advantages will 35 hereinafter appear.

The invention consists in the novel construction and combinations of parts, as hereinafter set forth.

40 In the accompanying drawings, illustrating the invention as applied to the machine of my co-pending application Serial No. 202,533, the numeral 2 designates the sup-

45 porting frame, made up partly of a plurality of vertical frame plates 3, each extending parallel to a denominational series of keys, and having a top plate 4 provided with a series of slots or perforations 5, engaged by the key stems 6, said stems usually

made up of planular or flat metal and disposed at right-angles to the planes of the plates 3, and said slots of form corresponding to the cross-section of said stems.

Each frame plate 3 relating to a denominational series of keys is provided with lower substantially vertical slots 10, in series, each key stem 6 having a lower extension or lug 11 laterally engaging and sliding in its respective slot 10 and provided with 55 an outer perforation 12, engaged by the lower end of the retracting spring 13, the upper end of said spring suitably connected to the framing, or to the frame plate 3, at 14.

60 The lateral lug 11 of each key stem is usually in the plane of the stem and has a downward and lateral extension or offset portion 15, one edge of which works adjacent to a lateral face of the adjacent plate 3. The 65 extension 15 is usually bent arcuately from the lug 11 and is, with the lug, readily insertible in the perforation of the top plate in placing the key in the machine, said lug and said extension also being readily removable 70 through the top plate perforation.

75 The upper ends of the slots 10 of each of the plates 3 are open, so that the key stems may be engaged therewith or let down therein from above, after said stems are engaged 80 with the perforations of the top plate, and means are provided to close the open upper ends of the slots, preferably consisting of movable latches 16, pivoted at their lower ends at 17 to the respective frame plates and 85 having upper forwardly extending ends 18, located over the laterally extending lower parts 11 of the key stems, said ends 18 laterally offset at 19 over the tops of the slots 10 and abutting against one edge of the cut-away portion 10' in the plate 3, to limit the 90 pivotal movement of the latch. The latches 16 will in this way limit the upward movement of the keys.

95 Lateral movement of each key stem in one direction will be limited by engagement of the part 15 of the stem with the adjacent plate 3, and lateral movement of the stem in the opposite direction will be limited by the laterally offset upper end 19 of the latch, 100

the key stem being thereby, at its lower portion, guided in a true path in its endwise or longitudinal movement.

The latches 16, being pivoted as stated, are releasable to open the upper ends of the slots 10, so that the key stems may be inserted in the machine in the assembly thereof, and withdrawn upwardly and out of the machine when required. Each latch is provided with a tail lever end 20, extending usually rearwardly from its pivot and adapted for the application of pressure in engaging the offset upper ends of the latch over and closing the upper ends of the slots, and reversely in releasing the latches, as stated. When the latches are in normal position, closing the upper ends of the slots, these tail lever ends 20, have their lower edges located in the same plane as the lower edges of the vertical frame plates 3, and when the assembled machine is placed in its outer casing, these tail ends engage the top surface of the horizontal base 21, of said casing, being thereby held or locked in position. The lower edges of the plates 3 rest upon the top surface of the base 21 and take the weight of the machine.

The latches are conveniently moved from released position, with their tail ends extending downwardly below the lower edges of the plates 3, pivotally to normal position, by pressing the otherwise assembled machine upon a horizontal or flat base.

To accomplish the release of the latches it is necessary to first lift the machine from the base 21, so that the tail ends of the latches will no longer be in the locking engagement aforesaid.

These latches have a frictional bind upon their pivots, so that they do not work easily, whereby, in assembling the machine, and prior to the association of the assembled machine with the outer inclosing and protecting casing 2', and the base 21 thereof, the latches will be held securely against accidental or casual pivotal movement, which would effect the release of the parts of the machine held in position thereby as previously stated.

I claim:

1. In registers, a stationary frame plate member and a reciprocatory key stem member, one of the members having a slot open at one end and the other member having an extension slidably engaging said slot, and releasable means for closing the open end of said slot.

2. In registers, a stationary frame plate having a slot open at one end, a reciprocatory key stem having an extension slidably engaging said slot, and a pivoted device carried by said plate and releasably closing the open end of said slot.

3. In registers, a frame plate having a

slot open at one end, a reciprocatory key 65 stem having an extension slidably engaging said slot, releasable means carried by said plate for closing the open end of said slot, and a casing member engaging the closing means and holding the same in active 70 position.

4. In registers, a vertical frame plate having slots open at one end, denominational keys having planular stems disposed at right-angles to said frame plate, said stems 75 having edge extensions slidably engaging said slots, and releasable means for closing the open ends of said slots.

5. In a register, a horizontal upper frame plate having openings, a vertical frame plate 80 having slots, denominational keys having stems working in said openings and provided with extensions working in said slots, and releasable means for retaining said extensions in said slots, said stems and said 85 extensions adapted upon release of the retaining means for movement to disengage the extensions from the slots and afterward for withdrawal through said openings.

6. In registers, an upper horizontal frame plate having openings, a vertical frame plate, denominational keys having planular stems disposed at right-angles to said vertical plate and having guiding pin and slot connection therewith including releasable 95 elements, said stems upon release of said elements capable of withdrawal through said openings.

7. In registers, an upper horizontal frame plate having openings, a vertical frame 100 plate, denominational keys having planular stems disposed at right-angles to said vertical plate and having guiding pin and slot connection therewith including releasable elements, register wheels, an actuator for one 105 of said wheels including a lever, said stems having shoulders in the planes of the stems and engaging said lever and upon release of said devices being capable of withdrawal through said openings.

8. In registers, a vertical frame plate, a depressible key having guiding pin and slot connection with said plate, the slot of said connection open at one end, means for releasably closing the open end of the slot of 115 said connection, and means for locking the closing means against release.

9. In registers, a supporting frame including a vertical plate having a slot, a key having a stem provided with an extension working in said slot, said extension having an offset portion engaging said plate to prevent lateral movement of the key stem in one direction.

10. In registers, a supporting frame including a vertical plate having a slot, a key having a stem provided with an extension working in said slot, said extension having an

offset portion engaging said plate to prevent lateral movement of said stem in one direction, and movable means engaging said extension to retain the same in the slot and serving also to prevent lateral movement of the key stem in the opposite direction.

5 11. In registers, a supporting frame, a depressible key having guiding engagement with said frame, including a releasable ele-

ment and a casing member having engagement with said element to hold the latter in active position.

In testimony whereof I affix my signature in presence of two witnesses.

GEORGE C. CHASE.
